BYPASS FITTING

Olney P. Yowell, Whittier, Calif., assignor to
 O. P. Yowell Service Company, a corporation
 of California

Application October 15, 1938, Serial No. 235,210

5 Claims. (Cl. 166—1)

This invention relates generally to oil well tools and more particularly to oil well tools having packing members adapted to engage the interior of a well casing, the invention being designed for use in combination with such tools.

The invention is particularly adaptable for use in combination with oil well tools known as cementing tools and tools known as perforation washers. Both cementing tools and perforation washers are ordinarily equipped with packing members which surround a central conduit member and are adapted to engage the inner wall of an oil well casing. In lowering or raising such a tool in a well some provision must be made for bypassing the fluid ordinarily present in the well past the packing members in order that the tool may be lowered or raised in the casing without moving the entire body of fluid before it or damaging the packing members. A short perforated section of pipe located above the tool is often used to effect a bypass. While the perforated pipe section permits of bypassing the fluid to opposite sides of the packing members during raising and lowering of the tool in the hole, it has the disadvantage that there is no practical way of preventing the member from acting as a bypass means when this is desirable.

Thus, with a perforated section of tubing above the packing members it is impossible to "spot" a chemical, oil or cement at the lower end of the tool for the reason that the material bypasses through the perforated pipe section above the tool. It is also often desirable to be able to "establish circulation" of fluid down through the tool and this is of course impracticable with this type of bypass.

Another type of bypass means used comprises a tube which is mounted interiorly of the main tubing member carrying the packing members. This bypass tube communicates with the exterior of the tool on opposite sides of the packing members. The difficulty with this type of bypass means is that it greatly restricts the usable cross sectional area of the main tube and therefore seriously interferes with the circulation of fluid or cement slurry therethrough. It is also true that with this type of bypass it is impracticable to spot a liquid at the bottom of the tool or force liquid from the bottom of the tool through the perforations in the casings in the region thereof for the reason that the pumped liquid is free to bypass up the bypass tube to a point above the uppermost packers.

Therefore, it is an object of this invention to provide a simple, efficient and improved device

for use in combination with a perforation washer or a cementing tool including a tubular section having packing members thereon and mounted at the lower end of a string of pipe which is effective as a bypass means and which may also be readily adjusted to prevent bypassing of fluid from the interior of the tubing to the exterior thereof.

It is also an object of this invention to provide a bypass fitting which may be installed in a conduit or string of pipe above the tool having packing members thereon adaptable to engage the inner walls of a well casing, to serve as a bypass means for the well fluid when the tool is lowered or raised in the hole.

It is also an object of this invention to provide a bypass fitting which is adapted to receive a member freely dropped in the tubing at the surface of the ground for the purpose of sealing off the bypass means and preventing the liquid interiorly of the bypass fitting from escaping through the bypass means to a point exteriorly of the fitting, but not preventing the flow of liquid from a point exteriorly of the fitting to the interior of the fitting through the bypass means.

These and other objects will be apparent from the drawing and the following description thereof. Referring to the drawing which is for illustrative purposes only;

Fig. 1 is a fragmentary sectional elevation of an oil well bore hole showing a cementing tool in place therein and showing the bypass fitting of this invention in combination therewith;

Fig. 2 is a sectional elevation of the bypass fitting of Fig. 1; and

Fig. 3 is a sectional plan view on line 3—3 of Fig. 2.

More particularly describing the invention, reference numeral 11 generally indicates a formation in which there is shown a bore hole 12 lined with perforated casing 13. In the casing is shown a cementing tool generally indicated by reference numeral 14. The upper end of this tool is connected to a string of pipe, or tubing 15 which leads to the surface of the ground and acts as a conduit and as a supporting member for the tool. Connected in the tubing 15 at a point above the tool is the bypass fitting of this invention generally indicated by reference numeral 16.

The cementing tool comprises a relatively long cement discharge conduit 18 which is provided at its lower end with a guide shoe 19. Immediately above the guide shoe the conduit is perforated at 20 to provide outlet means for the cement. A

guide collar 21 is mounted on the conduit 18. Above the collar 21 are mounted packing members 22 and 23 while a third packing member 24 is mounted below the collar immediately above the perforations 20.

The upper end of the conduit 18 is mounted in the fitting 16 which in turn is mounted on the lower end of the tubing 15. For the purpose of illustration the cementing tool is shown resting on a cement bridge 27. An upper bridge 28, which has been drilled through prior to lowering the cementing tool in the well is also shown. The bridges are for the purpose of preventing migration of cement beyond the water strata to be cemented off.

Referring to Figs. 2 and 3 for details in the construction of the bypass fitting 16 of this invention, reference numeral 30 designates a hollow ended member internally threaded at each end at 31 and 32 respectively. Between the hollow ends of the fitting is a central bridging portion generally indicated by reference numeral 33. This bridge portion is provided at its upper end with an outwardly flared shoulder 34 and is also provided with an open portion 35. Transversely cutting the bridge portion at substantially a 45° angle is a bore 36 which forms the bypass passageway. This bore is enlarged at its outer end at 37 to accommodate a valve seat insert 38. A ball 39 is provided which, when dropped in the tubing, will seat on the insert 38 and thereby act as an inwardly opening check valve when in position. The bridge portion 33 is also provided with a plurality of longitudinally disposed openings 40 which are provided for the purpose of establishing communication through the fitting.

With this construction when the bypass fitting 16 is mounted in the tubing above the tool 14, or a similar tool, the tool may be readily lowered into the well by reason of the fact that the fluid located below the lowermost packer 24 will be forced into the conduit 18 and upwardly in that conduit through the passageways 40 in the fitting 16, and downwardly and outwardly through passage 36. In this manner the fitting 16 acts as a bypass means for bypassing fluid past the packing members 22, 23 and 24. When the tool is being lowered in the well, ball 39 is retained at the surface of the ground and is not used in connection with the fitting.

After the tool is in place at the desired point in the well, it is possible to "establish circulation" downwardly through the tubing 15 and downwardly through the fitting 16 so as to cause the fluid to emerge through the perforations 20 at the lower end of the tool by first dropping the ball 29 into the string of pipe so as to prevent the bypassing of the fluid downwardly and outwardly through the passage 36. Thus it is possible to "spot" a chemical or other substance at the bottom of the tool without having any of the substance escape from the conduit means above the tool in the region of the bypass means as would be the case where the ordinary perforated section of pipe is used as a bypass means. It is also true that any liquid forced out through the holes 20 will not have a chance to migrate or bypass to a point above the uppermost packer as would be the case if a bypass tube were used communicating with the exterior of the tool at points above the uppermost packer and below the lowermost packer.

When it is desired to remove the tool from the hole, this may readily be done inasmuch as the fluid externally of the tool and above the packer

22 is free to be bypassed downwardly through the interior of conduit 18 inasmuch as the fluid is free to enter the bypass fitting 16 through passage 36. It should be noted in this connection that the ball closure member 39 will not prevent bypassing of fluid from a point exterior of the fitting to the interior thereof since such a passage of fluid tends to unseat the ball valve.

As was pointed out above, the bypass fitting is designed for use in connection with perforation washers and certain of these washers having packing members disposed both upwardly and downwardly. With tools having upturned packing members, the bypass feature of this invention as described in the preceding paragraph is particularly important, since the fluid cannot pass between the upturned packing members and the casing without damaging the packers.

It often becomes important to be able to establish circulation downwardly in the casing exteriorly of the tool to the bypass fitting 16 and this operation is possible with the bypass fitting of this invention. Thus, if in a cementing operation more cement is introduced into the tubing 15 than can be taken by the formation this will leave a column of cement above the bypass fitting in the tubing 15. If this cement is not immediately removed, it will harden and set in the tubing. To obviate this possibility, the cement may be forced out of the top of the tubing 15 by circulating fluid downwardly between the casing and the tubing and this fluid will enter the bypass through passage 36 and force the cement out ahead of it.

While the invention has been shown in connection with a particular type of cementing tool, the device of this invention is adaptable for use in combination with other types of tools. Although shown as a separate fitting, it is contemplated that the bypass means could be built directly into an oil well tool as an integral part thereof. It is also true that although a particular design of bypass fitting has been shown, it is possible to change this design somewhat without departing from the scope of the invention and it is intended to cover such changes as come within the scope of the claims.

I claim as my invention:

1. For use in a well having a casing therein, an open string of pipe and a packer on said pipe engaging said casing; bypass means at a point above the packer in said pipe, said bypass means having a passageway from the interior of said string of pipe to the exterior thereof; and closure means for said passageway, dropable through said pipe.

2. For use in a well having a casing therein, an open string of pipe, a tool at the lower end of said string of pipe; a packer on said tool engaging the casing; bypass means in said tool, said bypass means having a passageway at a point above the packer from the interior of said tool to the exterior thereof; and closure means for said passageway dropable through said pipe.

3. In an oil well tool adapted to be mounted on the end of a string of pipe for use in a well having a casing therein and a conduit means having a casing engaging packing member therein; a bridging portion in said conduit means above said packing member, said bridging portion having an opening therein to permit passage of fluid therethrough and having a bypass port extending downwardly and outwardly therein providing communication between the upper end of said bridging portion and the exterior of said tubular

means; said bypass port being adapted to receive a closure member dropped in the upper end of the string of pipe as a free body to prevent bypass of fluid from the interior of said tubular means to the exterior thereof.

5. For use as described, a bypass fitting comprising: a hollow ended member having a passageway establishing communication between the ends thereof, said member having a downwardly and outwardly extending bypass port communicating with the exterior thereof, said member having a bridging portion in the region of the inner end of said bypass port, said bridging portion having guide faces for directing an object to the inner end of said bypass port, said bypass port being adapted to receive a closure member dropped into said fitting to prevent bypass of fluid from the interior of said member to the exterior thereof.

5. For use in combination with a string of pipe and an oil well tool having packing members mounted on a conduit means, a bypass fitting comprising: a member having hollow end portions, said member having a bridge portion separating the hollow end portions, said bridge portion having a passageway establishing communication between the hollow end portions and having a downwardly and outwardly extending bypass port communicating with the upper hollow end portion and exteriorly of the member, said bypass port being adapted to receive a closure member dropped in the upper end of the string of pipe as a free body to prevent the bypass of fluid from the interior of said member to the exterior thereof.

OLNEY P. YOWELL.
